3 Claims. (239—563)

The present invention relates to a nozzle for atomizing liquid substances and is particularly directed to a nozzle for spreading insecticides from an aircraft for the extermination of harmful insects.

Harmful insects in agriculture and in forests are frequently dealt with by spreading insecticides from aircraft, which are provided with devices enabling a uniform spreading of the substance over the stricken area.

The insecticide substances are rather frequently used in the form of solutions or emulsions thereof, which must be atomized into fine particles to obtain a perfect result. The atomization is achieved by forcing the solution or emulsion, under pressure, through a number of nozzles, which are usually arranged along the entire wing span of the aircraft. Thus, a large number of nozzles is required, and all of these nozzles must be adjustable if the rate of discharge of the atomized liquid has to be changed. In addition a check valve has to be provided between each nozzle and the distributing mains to prevent a trickling off of drops of the insecticide from the nozzles after cutting off the supply of the liquid. The existing arrangements are therefore rather complicated and expensive and the width of the treated area is comparatively small.

It is an object of the present invention to provide a combined nozzle, which provides for spreading of the atomized substance over a comparatively wide area and which, at the same time, allows adjustment of the rate of discharge of the spread substance.

The above, and other objects, features and advantages of the invention, will be apparent in the following detailed description of an illustrative embodiment thereof which is to be read in connection with the accompanying drawing, wherein:

Fig. 1 is an elevational view, partly broken away and in longitudinal section, of a nozzle embodying the invention; and

Fig. 2 is a transverse sectional view taken along the line 2—2 of Fig. 1.

Referring to the drawing in detail, it will be seen that the nozzle embodying the present invention comprises a substantially tubular body 1 provided with four longitudinally arranged rows of grooves or slots 2 cut in the outer surface and lying in planes which are perpendicular to the longitudinal axis of the body 1. Each groove or slot 2 has a crescent-like configuration so that its bottom surface 2a (Fig. 2) is arcuate. The depth of the cut defining each groove 2 is greater than the thickness of body 1 so that a rectangular opening 3 is formed at the inner surface of the body 1 where each groove 2 intersects that inner surface, the width of this groove determining the dimension of the square or rectangular opening 3 in the direction parallel to the longitudinal axis of body 1. The grooves or slots 2 are spaced apart in the respective longitudinal rows so that the openings 3 form a helix on the body 1. The machined grooves or slots 2, with the openings 3 defined thereby, form the external part of a so called "flat nozzle."

A tubular bushing 4 fits tightly inside the body 1, and

2

has four longitudinal grooves 5 which are circumferentially spaced apart in the outer surface of bushing 4 so as to extend across the openings 3 of the body 1. The width of the longitudinal grooves 5 in the bushing 4 may be approximately equal to the width of the grooves 2 in the body 1 and determines the dimension, in the circumferential direction, of the rectangular or square nozzle orifice defined by each opening 3 and a groove 5. The groove 5 in the bushing 4 forms the internal part of the so called "flat nozzle." Since it is easily possible to maintain during manufacture, with practically any desired accuracy, the width of the grooves 2 and 5, it is thus also possible to accurately maintain the dimensions of the nozzle orifices. The grooves 5 communicate with the inner space of the bushing through openings 6 which are displaced, in the longitudinal direction, with respect to the openings 3 so as to avoid the direct issuing of the liquid from the openings 6 through the nozzle orifices.

The body 1 and the bushing 4 are closed at one end 20 by a plug 7. This plug 7 is provided with a threaded bore through which an adjusting screw 8 extends. A tubular sleeve 9 is arranged slidably on the body 1. This sleeve 9 is provided, at one end, with a packing 10 to prevent leakage of the liquid from between sleeve 9 and body 1, while the other end of sleeve 9 is closed by an end wall 11 through which the screw 8 extends rotatably. The screw 8 has a collar held against axial displacement relative to end wall 11 so that rotation of screw 8 causes axial displacement of sleeve 9 along body 1. A supply orifice 12 is provided at the end of the body 1 remote 30 from plug 7.

The insecticide substance or any other substance to be atomized is supplied under pressure to the nozzle through the orifice 12 and bore 13 into the internal cavity of the bushing 4, from which it passes through the holes 6 into the grooves 5 and escapes through the nozzle orifices defined at the intersections of the grooves 5 and openings 3. The amount of the atomized liquid is adjusted by operating the screw 8, by means of which the tubular 40 sleeve 9 is axially displaced with respect to the body 1, to cover a larger or smaller number of the nozzle orifices.

Thus a substantial simplification of the spreading device is achieved with simple means being provided for adjustment of the amount of atomized substance, and 45 with locating of the spreading device on the aircraft being facilitated. When taking advantage of the vortices formed at the edges on the ends of the wings, the width of the treated area during one passage of the aircraft may be increased up to 70%. The exact dimensions of the 50 nozzle orifices may be very easily maintained during manufacture, so that the combined nozzle according to this invention is exact and economical in performance and in manufacture.

What I claim is:

- 55 1. A nozzle for atomizing liquid substances comprising a tubular body having longitudinally arranged rows of crescent-shaped slots extending inwardly from the outer surface of the body in planes perpendicular to the longitudinal axis of said body and intersecting the inner surface of the latter to define rectangular openings therein, a tubular bushing fitting closely in said body and having longitudinally extending grooves in its outer surface which are circumferentially located to extend across the rectangular openings defined by the longitudinally arranged rows of slots so that said slots and grooves cooperate 60 to define the dimensions of nozzle orifices in the circumferential and axial directions, respectively, of said body and bushing, said bushing further having radial holes opening from the interior of the bushing into said grooves 65 at locations along the latter which are spaced in the axial direction of said bushing from the rectangular openings 70 at locations along the latter which are spaced in the axial direction of said bushing from the rectangular openings

at the inner surface of the body intersected by the related grooves, and means defining an inlet for the liquid substance to be atomized opening into said interior of the bushing so that the liquid substance passes radially through said holes and then axially along said grooves prior to issuing radially through said nozzle orifices.

2. A nozzle as in claim 1, wherein said slots are spaced apart in the related longitudinally arranged rows to dispose said rectangular openings along a helix at said inner surface of the body.

3. A nozzle as in claim 2, further comprising a sleeve axially slidable on said tubular body to cover selected numbers of said slots at the outer surface of the body

and thereby close the related nozzle orifices, and means engaging said sleeve and body and operative to effect axial displacement of the sleeve relative to the body.
